Fig. 3

Fig. 4

Fig. 1 is a front elevational view of a photographic flash holder safety guard or similar article, showing my new design;

Fig. 2 is a side elevational view, the opposite side being substantially a mirror image thereof;

Fig. 3 is a rear elevational view; and

Fig. 4 is a bottom elevational view thereof.

The drawing figures are diagonally lined to indicate transparency.

The broken line showing of a flash holder in Figs. 1 and 2 is for illustrative purposes only.

I claim:

The ornamental design for a photographic flash holder safety guard or similar article, as shown and described.
